UNITED STATES PATENT OFFICE.

WILLIAM H. GARDNER, OF NEW HAVEN, CONNECTICUT.

DESIGN FOR A BOX.

SPECIFICATION forming part of Design No. 17,982, dated December 27, 1867.

Application filed November 16, 1867. Serial No. 255,371. Term of patent 7 years.

To all whom it may concern:

Be it known that I, WILLIAM H. GARDNER, residing at New Haven, in the county of New Haven and State of Connecticut, have invented and produced a new and original Design for Boxes; and I do declare the following to be a full, clear, and exact description of the same, reference being had to the accompanying drawings, which form a part of this specification.

Figure 1 is a perspective view of my newly-designed box. Fig. 2 is a similar view of the body thereof, and Fig. 3 is a similar reverse view of the box cover.

The leading feature of my design consists in a Y-shaped outline for a box and the representation of a keg or cask upon such box.

The body of the box consists of the main part A, constituting the stem of the Y, and the diverging arms B B, constituting the branches thereof.

The cover of the box consists of the main

part C, constituting the stem of the Y, and the diverging arms D D, constituting the branches thereof, the body and cover fitting together like any ordinary box.

As herein shown, the body of the box is provided with linings of lace paper, E. As herein shown, also, the box-cover is provided with the representation of a keg, F; the form of box and the keg suggesting the word "Yale."

I claim—

The design for a box herein shown and described, the same consisting of the Y-shaped outline for the box and the representation of an ale-keg upon the box.

In testimony whereof I have signed this specification in the presence of two subscribing witnesses.

WM. H. GARDNER.
